CLAIM

The ornamental design for an infant support pad, as shown and described.

DESCRIPTION

FIG. 1 is a top, left side, and front perspective view of an infant support pad showing my new design, the right side being a mirror image of that shown; FIG. 2 is a front elevational view thereof; FIG. 3 is a rear elevational view thereof; FIG. 4 is a top plan view thereof; and, FIG. 5 is a bottom plan view thereof.
